PATENT GOWN

Stanley A. Weiser, Clayton, Mo., assignor to
 'Angelica Uniform Company, St. Louis, Mo., a
 corporation of Missouri

Application December 29, 1952, Serial No. 328,293

2 Claims. (Cl. 2-114)

1 This invention relates in general to garments and, more particularly, to certain new improvements in the construction of patient gowns.

It is a primary object of the present invention to provide a patient gown openable in the back and with rear sections having overlapping tabs for garment-closing attachment at points on opposite sides of the neck opening spacedly from the outer end of the adjacent shoulder whereby a smooth surface is provided across the back of the garment, unbroken by any discomfort-causing agents, such as the snaps, seams, buttons, and the like, disposed in the rear sections of currently used patient gowns.

It is a further object of the present invention to provide a patient gown having closure means which are readily accessible when the patient is in reclining position to thereby minimize the patient's discomfort in making change of garment; which gown, while preserving the modesty of the patient, permits of ready exposure for examination purposes; and which gown is economically constructed for comfortable and durable wear.

With the above and other objects in view, my invention resides in the novel features of form, construction, arrangement, and combination of parts presently described and pointed out in the claims.

In the accompanying drawing:

Figure 1 is a front view of a patient gown constructed in accordance with and embodying the present invention;

Figure 2 is a partial rear view of the patient gown showing the rear portions in closed position;

Figure 3 is a partial rear view of the gown with one rear section unsecured; and

Figure 4 is a partial rear view of the gown showing the rear sections in full open position.

Referring now by reference characters to the figures which illustrate the preferred embodiment of the present invention, A designates a garment or gown of non-fitting character for use by hospital patients. The garment A comprises broad, wrist-length sleeves 1, 2, of the so-called raglan type and a body 3, having a front section 4, a pair of rear sections 5, 6, and a plain neck opening 7. The front section 4 is preferably designed for termination of its lower edge below the wearer's knees, and is secured along its opposite lateral edges, as by side seams 8, 9, to the rear sections 5, 6, respectively, between its lower edge and the lower ends of arm holes a, b. Said arm holes a, b, are respectively defined by the

diagonally extending upper side edge portions 10, 11, of the front section 4 and those of rear sections 5, 6, designated 12, 13, respectively; said diagonal portions 10, 11, 12, and 13, terminating at the neck opening 7. Sleeves 1, 2, are each comprised of a pair of symmetrical sections 14, 15, secured together by inner and outer seams 16, 17, with the former extending from a wrist placket 18 to the lower end of the arm hole a or b, while the latter seam progresses from the wrist to the neck opening 7, substantially intermediate the adjacent diagonal upper edges of the front section 4 and rear sections 5, 6, for disposition along the wearer's shoulder. As shown, the sleeves 1, 2, are of the raglan type to provide ample room for the wearer's arms for enhanced comfort. Each sleeve 1, 2, is provided with the wrist placket 18 and cooperating button and button holes, designated broadly 19, for optional closing of the wrist portions.

The rear sections 5, 6, being secured along one of their side edges to the front section 4 and to the sleeves 1, 2, respectively, are free from each other along their opposite side edges but are of such width as to fall into back-closing relation when the garment is in worn position to prevent unnecessary exposure of the patient's body, yet permitting ready access for examination or treatment purposes. At the upper ends of the free or confronting side edges of rear sections 5, 6, there are provided oppositely-projecting, relatively short, narrow tabs or extensions 20, 21, respectively, for overlapping relationship across the upper portion of the wearer's back for detachable securing at their outer ends to the shoulder portions of the sleeves 1, 2, respectively, adjacent the neck opening 7, and spacedly from the outer edge of the adjacent shoulder, for maintaining the garment in wearing position. The upper edges of the tabs 20, 21, are continuous with that of their associated rear sections 5, 6, respectively, so as to complete the definition of the neck opening 7 and to be in mutual registration when in overlapped position to present a neat appearance to said neck opening 7. Adjacent the outer end of the tab 20 and on the normally outer face thereof there is provided a button hole 22 for engagement therein of a button 23 secured to the outward side of the shoulder portion of the sleeve 2, proximate the neck opening 7. The tab 21, which is designed to be overlapped by tab 20, is provided with a button 24 for engagement within and projection outwardly through a button hole 25, formed in the sleeve 1 in corresponding relation to the button 23. The

tab 20 is thus buttonable to the outside whereas the tab 21 is securable to the inside. It is, of course, clearly obvious that other closure members, such as snap fasteners, could be utilized, if desired. The tabs 20, 21, are of such limited length as to terminate at the wearer's shoulder when the garment is in worn position, and are of such restricted width as to present their outer margins in spaced relation to the outer end of the wearer's shoulders.

Adjacent the neck opening 7 there are provided reinforcing, facing sections indicated 26, and the margins of the garment portions forming the neck opening 7 are bound, as by a tape binding 27, with all seams being reinforced for endowing the garment A with durability.

It will be seen that the closure means are positioned to allow the garment to extend smoothly across the wearer's back whereby no discomfort will be occasioned when the wearer is in reclining position, such as by the closure means provided along the confronting portions of the rear sections of gowns heretofore generally used. The garment A is thus so uniquely constructed as to assure the patient maximum comfort and thereby conduce greatly to morale. The buttons 23, 24, are presented at readily accessible points so that the unbuttoning and buttoning operation can be easily accomplished, even by the patient if capable, while the patient is reclining whereby a change of garment is attended with minimum disturbance.

It should be understood that changes and modifications in the form, construction, arrangement, and combination of the several parts of the patient gown may be made and substituted for those herein shown and described without departing from the nature and principle of the present invention.

Having thus described my invention, what I claim and desire to secure by Letters Patent is:

1. A patient's gown comprising a body having a front section and first and second rear sections, each of said rear sections having forward and

back lateral edges and being secured along their forward lateral edges to opposite side edges of the front section, said rear sections each having its back lateral edge free for forming an openable back, a pair of sleeves each being secured to the front section and to one rear section, the upper ends of said sleeves defining portions of a neck opening, first and second tabs secured to and projecting in opposite directions from the back lateral edge of said first and second rear sections respectively adjacent the upper end of the related rear section, the upper portion of one sleeve having a button hole adjacent the neck opening, the other sleeve having a button in corresponding relation to the button hole of the other sleeve, said first tab having a button adjacent its end and on its normally rearward face for engagement with in the button hole of said one sleeve, said second tab having a button hole adjacent its end for engagement therein of the button on said other sleeve, whereby said second tab will overlie said first rear section and said first tab will underlie said second rear section when the same are in secured condition.

2. A patient's gown as defined in claim 1 wherein the said first and second tabs are of restricted width whereby the normally outer margins thereof are spaced from the outer edge of the adjacent shoulder of the wearer and wherein in the back lateral edges of each rear section define substantially vertical lines which are in substantially parallel relation when the garment is in worn position.
